UNITED STATES PATENT OFFICE.

ZEBULON DAVIS, OF CLEVELAND, OHIO.

VAPOR-STOVE.

SPECIFICATION forming part of Letters Patent No. 362,725, dated May 10, 1887.

Application filed August 3, 1886. Serial No. 209,895. (No model.)

To all whom it may concern:

Be it known that I, ZEBULON DAVIS, of Cleveland, in the county of Cuyahoga and State of Ohio, have invented certain new and useful 5 Improvements in Vapor-Stoves; and I do hereby declare the following to be a full, clear, and exact description of the invention, such as will enable others skilled in the art to which it pertains to make and use it, reference being had to the accompanying drawings, which form part of this specification.

My invention relates to an improvement in vapor-burners; and it consists in, first, the combination of the induction-tube, having a 15 combustion-chamber formed upon its top, with the generating-chamber, which is made in a separate and distinct piece, and which is placed upon the top of the combustion-chamber, there being left a sufficient space between the two 20 parts to allow the generating-flame to pass out between them; second, the combination of the generating-chamber, having an opening through its center and a suitably-shaped recess in its top, with a removable perforated 25 cap, which is placed upon the top of the chamber and over the opening and recess; third, the combination of the generating-chamber, having an opening through its center and a suitable recess in its top, with a lever, upon which 30 the perforated cap is placed, and by means of which lever the cap can be moved over or to one side of the opening through the chamber, as may be desired; and fourth, the combination of the induction-tube, having the combustion-chamber formed upon its top, with the generating-chamber having an opening through its center, a suitably-shaped recess in its bottom, and another recess in its top, and a lever for 35 moving the perforated cap back and forth in relation to the opening through the center of the chamber, all of which will be more fully described hereinafter.

The object of my invention is to produce a vapor-burner which is adapted for use in connection with a vapor-stove of the ordinary construction, but which is specially intended for plumbers' and tinners' use, and by means of which either a quiet steady flame may be produced, for heating purposes, or a forcible blow-50 pipe flame, which is specially adapted for use in plumbers' furnaces.

Figure 1 is a vertical longitudinal section

taken through a burner embodying my invention. Fig. 2 is a plan view showing the cap in one position in solid lines and in another in dotted lines. Fig. 3 is a side elevation of the burner complete, showing the different forms of flames that are produced at will. Fig. 4 is a vertical section taken through the burner at right angles to Fig. 1.

A represents the stand-pipe, which is connected to the generating-chamber B at its upper end. This generating-chamber is preferably made circular, as hereshown, and is made entirely separate and distinct from the combustion-chamber C, which is formed upon the upper end of the induction-tube D. In this chamber C the combustion takes place, and the flame is partially retained for the purpose of heating the generating-chamber when the 60 perforated cap is moved to one side. Through the center of this combustion-chamber is made a suitable opening, E, of any desired shape or size, for the purpose of producing a forcible blow-pipe flame, such as is used by plumbers 65 for melting. In the top of the chamber is formed a recess, F, either of the shape here shown or any other that may be preferred, for the purpose of allowing the gas, which passes up through the central opening, E, to spread 70 evenly over the top of the burner and to pass through the openings in the perforated cap G when the burner is being used to produce a quiet heating flame, such as is produced by vapor-burners of the ordinary construction. 75 In the under side of this generating-chamber is also formed a recess, H, which extends around the opening E, and which forms an impinging-chamber for the gas to catch in. When a plumber's flame is being produced, 80 the lower edge of the opening E catches a portion of the rising vapor and deflects it outward toward the edges of the combustion-chamber, and this vapor in burning heats the generating-chamber, so as to keep up a constant and rapid generation of gas. Were it not for this impinging-chamber, the force of 85 the gas would carry it up through the opening E, above the burner, and not come in contact with the generating-chamber sufficiently to generate a sufficient quantity of vapor. On the under side of this generating-chamber are formed a number of projections, I, which bear 90 upon the top of the combustion-chamber and

serve to raise the generating-chamber sufficiently above the top of the combustion-chamber to leave a small opening, *a*, between the generating-chamber and the upper edge of the combustion-chamber, as shown in Figs. 1 and 4, so that the generating-flame can pass between them while the burner is being used to produce a quiet heating-flame. This generating-flame is not produced while the perforated cap is moved to one side so as to produce a plumber's flame.

Pivoted at one side of the generating-chamber is a lever or handle, *J*, upon the inner end of which the perforated cap is placed. When this cap is moved directly over the top of the generating-chamber, all of the vapor is made to pass through this cap, and then only a quiet heating-flame is produced. It is while this cap is in position that the generating-flame rises around the edge of the generating-chamber. When the lever or handle is moved so as to carry this perforated cap to one side, then a plumber's flame is produced.

Heretofore a convertible tinner's and plumber's furnace has been made; but never has there before been made a burner which would produce either a quiet heating-flame or a plumber's flame at the will of the operator. A patent was granted to me for a convertible furnace which could be used by either a tinner or a plumber; but the burner was not convertible and the flame could not be changed from a noiseless to a forcible blow-pipe flame. This patent bears date of February 24, 1885, and No. 312,825.

A burner which is suitable for use in heating tools for a tinner must be quiet, inasmuch as it is used in a building; but a quiet flame is not sufficiently powerful for a plumber's use, and hence a burner which is not convertible will not answer for the purposes of both. The object of this invention has been to produce a burner which is suitable either for a plumber's or a tinner's use by simply moving the handle or lever which carries the perforated cap.

In Fig. 1 is shown an apparatus in connection with a burner, and which is adapted to be used either for a plumber's or a tinner's furnace. Around the burner is placed an outer sheet-iron drum or hood, *L*, and inside of this hood is placed the iron lining *N*, which is provided with a hinged lid, *O*, so as to shut in the heat when being used by a tinner. When the furnace is being used by a plumber, the lining *N* is entirely removed, and then a plumber's pot is placed within the hood *L*, and the perforated cap is moved to one side, so that a plumber's flame is produced. When it is desired to keep the burner heated at the least possible expenditure of fluid, a hinged cap, *P*, which is placed inside of the lining *N*, is dropped down upon the top of the burner, so as to cover the perforated cap, thus permitting the vapor to escape only between the lower edge of the generating-chamber and the upper edge of the combustion-chamber. As soon as the cover *P* is raised

the gas burns both from the perforated cap and the edge of the combustion-chamber. This cover *P* when not in use will drop back 70 into a recess formed in the lining *N*, so as to be out of the way. Through both the outer hood or jacket and the lining is made a suitable opening, through which the tools are to be inserted for the purpose of being heated 75 by the flame of the burner, and which doors are capable of being closed when the furnace is to be used by a plumber for melting purposes.

I do not limit myself to any precise construction or arrangement of parts, for this may be varied at will without departing from the spirit of my invention.

Having thus described my invention, I claim—

1. The combination of the generating-chamber, a controlling-valve, the induction-tube, the combustion-chamber having an opening through its top, and a movable perforated cover, which can be made to cover over the 90 opening through the top of the combustion-chamber, substantially as shown.

2. The combination of the generating-chamber *B*, having an opening, *E*, through it, the combustion-chamber *C*, upon the top of which 95 the generating-chamber is placed, a perforated cap, and a lever or handle for moving the cap in relation to the opening through the generating chamber, substantially as described.

3. The combination of the generating-chamber, having an impinging-chamber or recess, *H*, formed in its under side, and an opening, *E*, through it, with the combustion-chamber *C*, upon which the generating chamber is placed, substantially as set forth.

4. The combination of the generating-chamber *B*, having an opening, *E*, through it, and the recess *F* in its top, the needle-valve, the induction-tube *D*, the combustion-chamber *C*, and the pivoted perforated cap *G*, substantially as specified.

5. The combination of the generating-chamber, having an opening through it, with the perforated cap, which is placed over the top of the opening, and the combustion-chamber, 115 there being left sufficient space between the edges of the generating-chamber and combustion-chamber to allow the generating-flame to be produced, substantially as shown.

6. In a vapor-burner, the combination of a 120 generating-chamber having an opening through it, a combustion or retaining chamber placed below the generating-chamber, and a movable cap or cover, whereby either a quiet heating-flame is produced or a forcible 125 blow-pipe flame for plumbers' use, substantially as set forth.

In testimony whereof I affix my signature in presence of two witnesses.

Z. DAVIS.
